UNITED STATES PATENT OFFICE.

CLORA J. SNIDEMAN AND FRANK H. HENLEY, OF WABASH, INDIANA.

SANITARY TRAY FOR CHAIRS.

1,021,901.

Specification of Letters Patent.

Patented Apr. 2, 1912.

Application filed June 10, 1910. Serial No. 566,146.

To all whom it may concern:

Be it known that we, CLORA J. SNIDEMAN and FRANK H. HENLEY, citizens of the United States, residing at Wabash, in the 5 county of Wabash and State of Indiana, have invented a new and useful Sanitary Tray for Chairs, of which the following is a specification.

In the manufacture of high chairs for the 10 use of very small children, it is customary to provide a tray which forms a permanent portion of the chair, this tray being generally mounted upon swinging arms so that it may be turned back over the head of the 15 child and extended down at the back. Such a tray is very difficult to keep clean because it is practically impossible to prevent accumulation of food in the cracks which necessarily occur in the wooden structure. 20 As the child grows larger the length of the tray supporting arms is too short to permit the tray to be swung over the head of the child and it then becomes difficult to seat and unseat the child.

25 The object of our present invention is to produce a chair provided with a detachable tray of such character that it may be formed without open joints, and of such character that it may be thoroughly and readily 30 cleansed.

A further object is to produce a chair, especially adapted for use with such a tray and of such form that, when the tray is removed, free access may be had to the seat.

35 The accompanying drawings illustrate our invention.

Figure 1 is a perspective view of the chair embodying our invention with the detachable tray in place; Fig. 2 a similar view of 40 a similar chair with the tray removed; Fig. 3 a fragmentary perspective showing a swinging tray form; Fig. 4 a fragmentary section of one of the tray-supporting arms; Fig. 5 a fragmentary section of a modified 45 form; Fig. 6 a plan of the tray-supporting arm shown in Fig. 5; Fig. 7 a fragmentary section of a modified form of connection between the removable tray and the tray-supporting arm; Fig. 8 a plan of a slightly 50 modified form of a retaining means, and Fig. 9 a side elevation thereof.

In the drawings, 10 indicates a chair of any desired form provided with a tray-supporting arm which may be a rigid part 55 of the structure as shown at 11 in all of the figures except Fig. 3, or may be a swinging

arm as shown at 11' in Fig. 3. The forward extremity 12 of arm 11 is of such form as to receive a detachable metal tray 13 and, if desired, may be detachably secured by a 60 screw 14, or otherwise, to the main body of the arm 11 or 11', as shown in Fig. 4.

Tray 13 is preferably formed by stamping from a single sheet of metal, or in such other way that there will be no open joints. For 65 commercial reasons it is preferable that the tray 13 be enameled, like common metal enameled ware so that it may present a smooth surface throughout to facilitate thorough cleansing.

In the form shown in Fig. 3, where the arms 11' are pivoted at 15, in an ordinary manner, to the back of the chair 10, the forward ends of said arms may be firmly connected by a thin board 16 which will lie 75 beneath the tray 13. It will be readily apparent that a considerable variety of forms of tray 13 may be provided without departing from our invention. In Figs. 1 and 4, the ends of the tray are first bent 80 down at 17 and then bent under at 18 so as to embrace the projecting end 12 of the supporting arm and a light spring 19 is secured to the body of the tray so as to co-operate with a retaining pin 21 carried by 85 the projecting end 12 of the supporting arm.

In Fig. 7 the tray 13 is provided at its extended ends, which overlie the supporting arm 11, with channels 22 which embrace the extended ends 12 of the arms 11. 90

In Figs. 8 and 9, the tray itself is not provided with any means for preventing tilting of the tray upon the supporting arms but, instead, a wire retainer 23 secured to the arm 11, is arranged so that the edge 95 13' of the tray will pass beneath retainer 23 when the tray is in its usable position.

It will be seen from the above that the tray may be readily detached from, or attached to, the supporting arms in order that 100 it may be conveniently cleansed.

We claim as our invention:

1. The combination, with a chair having a pair of arm rests arranged above and one at each side of the seat and each of said arm rests having a longitudinal pocket formed at its outer end, of a pair of tray-supporting extensions each comprising a portion adapted to fit within an arm pocket and another portion adapted to receive a tray, 110 and a one-piece metal tray provided at its ends with pockets formed to detachably re-

ceive the exposed ends of the tray-supporting arms.

2. As an article of manufacture, a detachable tray for chairs comprising a one-piece metal tray portion having no open joints, and extensions at each end formed to detachably coöperate with receiving arms of a chair.

In witness whereof, we, have hereunto set

our hands and seals at Wabash, Indiana, this 10
third day of June, A. D. one thousand nine
hundred and ten.
